A. Bloesonto

UNITED STATES PATENT OFFICE.

LEWIS D. ADAM, OF JET, OKLAHOMA.

FISH BAIT.

Application filed June 9, 1924. Serial No. 718,947.

To all whom it may concern:

Be it known that I, LEWIS D. ADAM, a citizen of the United States, residing at Jet, in the county of Alfalfa and State of Oklahoma, have invented certain new and useful Improvements in Fish Baits; and I do declare the following to be a full, clear, and exact description of the invention, such as will enable others skilled in the art to which it appertains to make and use the same.

My invention relates to new and useful improvements in fish bait and the principal object is to provide an extremely simple and inexpensive device of this character which effectively simulates one of the large black bugs which inhabit a great many bodies of water, numerous kinds of fish being very fond of feeding upon such bugs.

In carrying out the above end, a further aim is to provide a body which is longitudinally divided into upper and lower sections, which sections secure flexible strips in place between them, with their ends projecting to simulate legs.

A further aim is to provide a construction in which the upper and lower sections of the body secure the shank of a hook, so as to connect such hook with the bait.

A still further aim is to so construct and associate the upper and lower sections of the body as to cause them to direct the leg-forming portions of the flexible strip, downwardly and outwardly in a very realistic manner.

With the foregoing in view, the invention resides in the novel subject matter herein-after described and claimed, the description being supplemented by the accompanying drawing.

Figure 1 is a top plan view.

Figure 2 is a bottom plan view.

Figure 3 is a longitudinal sectional view on line 3—3 of Fig. 1.

Figures 4 and 5 are transverse sectional views on lines 4—4 and 5—5 of Fig. 2.

Figure 6 is a perspective view of one of the flexible, leg simulating strips.

In the drawing above briefly described, the numeral 1 designates a body simulating that of a bug. This body is preferably of hollow form, and in most instances, is stamped from sheet metal in two sections, that is an upper section 2 and a lower sec-

tion 3, both of which may be stamped in any desired manner to simulate natural characteristics of the bug body being represented. In the preferred construction, the lower section 3 is provided with a flat outwardly extending flange 4 throughout its perimeter, and this flange is outwardly stamped at the ends of the body as indicated at 5 to provide upwardly facing grooves disposed longitudinally. Similarly, the flange is stamped as indicated at 6 to provide upwardly facing transverse grooves at the sides of the body. A hook 7 is located at the rear end of the body and is provided with a forwardly extending shank 8 which is received in the longitudinal grooves of the flange 4, said shank being preferably provided at its front end with an eye 9, although it might if desired be equipped with other provision for connecting a line thereto. The transverse grooves of the flange 4 receive the intermediate portions of a plurality of flexible strips 10 which are preferably formed of rubber. The end portions 11 of the strips 10 preferably diverge rearwardly to represent legs. Due to the construction described below, these portions 11 are also caused to decline outwardly from the body.

The upper section 2 of the body 1 rests on the lower section 3 and holds the strips 10 and the shank 8 in place, said upper section preferably having tongues 12 bent around the flange 4 to tightly secure the two sections together. If desired, the seam between these sections may be waterproofed so as to exclude water from the interior of the body, but this is not absolutely essential.

As shown most clearly in Figs. 2 and 4, the upper body section 2 is preferably of slightly greater width than the lower section 3, so that the edge portions of said upper section will force downwardly on the leg simulating portions 11 of the strips 10, thus causing said portions to assume outwardly declined positions with respect to the body, so that they more effectively simulate the legs of a bug.

The device is extremely simple and inexpensive, may be rapidly and easily manufactured, and will be highly efficient and generally desirable.

Excellent results may be obtained from

the details disclosed and they are therefore preferably followed, but within the scope of the invention as claimed, minor changes may of course be made.

5 I claim:

1. A fish bait comprising a hollow elongated body horizontally divided into upper and lower sections which are secured together, and transverse flexible strips between 10 the two body sections and projecting laterally therefrom, said upper section being of slightly greater width than the lower section and forcing the projecting portions of said strips downwardly to inclined positions 15 to represent legs.
2. A fish bait comprising a hollow elongated body formed of upper and lower sections, the lower section having a horizontal flange at its upper edge, said flange being 20 formed with longitudinal grooves at the

front and rear ends of the body and with transverse grooves at the sides of said body, a hook at the rear end of the body having a forwardly projecting shank in said longitudinal grooves, transverse flexible strips 25 whose intermediate portions are received in said transverse grooves, the upper section of the body being in contact with said strips and shank to hold them in place, and tongues on said upper section bent inwardly 30 around said flange to secure the two sections together.

3. A structure as specified in claim 2; said upper section being slightly wider than the lower sections and forcing the end portions of said strips downwardly to inclined 35 positions.

In testimony whereof I have hereunto affixed my signature.

LEWIS D. ADAM.
